UNITED STATES PATENT OFFICE

100,607

DESIGN FOR AN ILLUMINATED SPOTTING BOARD

George G. Stringer, Lubbock, Tex.

Application March 11, 1936, Serial No. 61,587

Term of patent 3½ years

To all whom it may concern:

Be it known that I, George G. Stringer, a citizen of the United States, residing at Lubbock, in the county of Lubbock and State of Texas, have invented a new, original, and ornamental Design for an Illuminated Spotting Board, of which the following is a specification, reference being had to the accompanying drawing, forming part thereof.

Figure 1 is a top plan view of an illuminated spotting board showing my new design.

Figure 2 is a view in front elevation thereof.

Figure 3 is an end elevational view.

I claim:

The ornamental design for an illuminated spotting board as shown.

GEORGE G. STRINGER.
